CONVEYOR AGITATOR MEANS AND CONTROLS
THEREFORClair R. Johnston, 1397 Firestone Parkway, Akron, Ohio
Filed Jan. 7, 1963, Ser. No. 249,720
8 Claims. (Cl. 198—230)

This invention relates to apparatus of the type that is used for separating dirt from articles dug from the ground and, for example, wherein the digging operation, large quantities of dirt are carried up into the apparatus of the invention intermingled with the dug articles and where the apparatus of the invention is to separate the dirt from the dug articles, which are to be retained and collected.

Attention is directed to my previous Patent No. 2,577,525 which illustrates some type of apparatus for digging potatoes and similar articles from the ground. In this type of apparatus, a relatively large, sturdy machine is driven along the field and, by a plow, or digging member provided thereon, a quantity of potatoes, or similar articles, such as peanuts, would be dug from the ground intermingled with a volume of the surrounding dirt in which the potatoes, peanuts, or the like have been grown.

In general, the previous machine, or similar types of apparatus, would move through the field and lift potatoes and dirt up into the apparatus. The apparatus might have means therein for separating the dirt, and possibly the weeds, or large stones from the articles to be retained, or else some of such actions might be manually performed.

While my previous apparatus has been reasonably satisfactory for performing these digging and separating functions, it is desirable to improve upon the results obtained, and especially upon the action of separating the excess dirt from the dug articles to facilitate ultimate recovery of the dug articles.

Particularly, the present invention relates to just a portion of the machine for separating the excess dirt from the dug articles and permitting such dirt to fall, or be deposited, back onto the field.

The general object of the present invention is to provide a novel and improved type of conveyor and associated means for moving dirt and dug articles thereover to separate the dirt therefrom, and characterized by the provision of adjustable impact forces on the conveyor at different portions of its movement through the apparatus.

Another object of the invention is to provide a relatively sturdy, easily adjusted, readily controlled means in apparatus of the class described to provide variable strength repetitive impacts on a conveyor at different portions thereof to jar and vibrate the conveyor to separate dirt from the conveyed material.

Another object of the invention is to position an open frame type of a conveyor with a horizontal reach therein and where support means are provided for the conveyor in such reach thereof, which support means for the conveyor have both upstream and downstream striking means, or rapper bars associated therewith by which controlled vibrating or striking forces can be applied to the conveyor as it moves along the apparatus in a downstream direction to cause dirt on the conveyor to be broken into small pieces and to fall through the conveyor and leave primarily only the desired articles on the conveyor.

Another object of the invention is to provide support means in association with a horizontal reach of a conveyor, which support means are accurately and easily varied in vertical relationship to the conveyor and position agitating means thereon in controlled relation to the conveyor to provide desired strength impacts on the conveyor as it moves through the apparatus.

2

The foregoing and other objects and advantages of the invention will be made more apparent as the specification proceeds.

Attention now is particularly directed to the accompanying drawings, where:

FIG. 1 is a diagrammatic view of conveyor and digging means used in association with the apparatus of the invention;

FIG. 2 is a plan view of a conveyor and associated support means therefor embodying the principles of the invention;

FIG. 3 is a side elevation, with some members removed and other members shown in vertical section, of the conveyor and support means shown in FIG. 2;

FIGS. 4, 5 and 6 are fragmentary vertical sections of the conveyor means of FIG. 3 taken on lines 4—4, 5—5 and 6—6, respectively, thereof; and

FIG. 7 is a fragmentary enlarged vertical section of a portion of the conveyor of FIG. 2.

When referring to corresponding members shown in the drawings and referred to in the specification, corresponding numerals are used to facilitate comparison therebetween.

Generally speaking, the present invention relates to apparatus particularly adapted for separating dirt from a mixture of dirt and dug articles where the apparatus includes a frame, an endless apertured conveyor, and means positioning the conveyor on the frame for movement through a fixed path including an upper horizontal reach, the apparatus including the improvement of a support member extending longitudinally of the conveyor immediately below the said horizontal reach thereof to be available for supporting the conveyor, adjustable support means engaging the support member to vary its position in relation to the horizontal reach of the conveyor, a rapper means operatively carried by the support member and movable to strike the conveyor in its horizontal reach to move the conveyor upwardly, and driven means positioned adjacent the rapper means to strike them and knock them against the conveyor with a variable force dependent upon the positioning of the support member in relation to the driven means.

Reference now is particularly directed to the details of the structure shown in the drawings, and FIG. 1 diagrammatically indicates a series of conveyors and associated means for processing a mixture, for example, of dirt and dug articles. These conveyors would be positioned on a suitable vehicle (not shown). Thus a plow, or similar digging means 1 is shown which can be forceably pushed into the ground and moved therealong. The plow 1 will push articles and the dug dirt up onto an elevator, or conveyor 2 from which the dirt, dug articles, weeds, and other members would pass to be deposited upon a horizontally extending conveyor 3 that is positioned on suitable members such as drums or positioning sprockets 4 and 5. On this conveyor 3, the dirt and dug articles are adapted to be vibrated to have a large portion of the dirt thereon shaken through the conveyor 3 to pass back onto the ground. Any large, or bulky items, such as weeds, grasses, large stones and the like would move from the conveyor 3 to a second separator conveyor 6 that may extend upwardly of the apparatus and can deposit the members thereon into any suitable receptacle, or otherwise process them, as desired. A second and horizontally extending conveyor 70 is positioned adjacent the discharge end of the conveyor 3 for receipt of the dug articles, and any remaining dirt and small stones therefrom.

As best shown in FIGS. 2 and 3 of the drawings, preferably the conveyor 3 is of an "open" construction to facilitate the passing of dirt and other small articles therethrough. The conveyor 3 hence is shown made from a

plurality of transversely extending cross bars 7 that are secured to longitudinally spaced portions of a plurality of carrier cables 8, as by means of U-bolts 9, or the like, which engage the cables 8 and extend through apertures in the cross bars 7 and have their ends riveted, welded, or otherwise secured to the cross bars 7, as indicated in FIG. 1.

The conveyor 3 is positioned to have a horizontally extending upper reach 10 provided therein, as shown in FIG. 3, and such conveyor 3 may be positioned at one end by a plurality of sprockets 4, that are secured to the downstream support shaft 11 which in turn is suitably journaled on a frame 12 for a vehicle on which the plow 1, elevator 2, conveyor 3 and associated means would all be positioned. This vehicle could be of the type referred to in my previously identified United States Letters Patent. The opposite, or upstream end of the conveyor 3 is positioned by any suitable members, such as a plurality of support rolls 13, that are, for example, journaled on or carried by a shaft 14 that extends transversely of the vehicle frame 12. However, it will be realized that both the upstream and the downstream supports for the conveyor 3 may, in general, be of any suitable type.

Positioned between the courses or reaches of the conveyor 3 are a pair of supports, tracks, or bars 15 and 16 that extend longitudinally of the conveyor 3 and usually aid in supporting the conveyor 3, as it moves along the horizontal upper reach 10 thereof. The conveyor 3 is shown as having a plurality of slides or plates 17 secured to the inner surface of the cross bars 7, which plates 17 would normally move along and engage with the upper surface of the tracks or bars 15 and 16 to facilitate movement of the conveyor through a fixed path. The position of these bars 15 and 16 with relation to the upper reach 10 of the conveyor is preferably accurately adjusted and controlled by individually adjustable positioning means that engage with the opposite ends of the bars 15 and 16, as hereinafter described. For example, at the upstream ends of these support bars 15 and 16, a hydraulic cylinder 18 is preferably positioned on the frame 12 at each side thereof and it has a suitable piston therein with a piston rod 19 extending from the cylinder. A control lever 20 is pivotally connected to the upper end of the piston rod 19 and it is, for example, secured to a control rod or shaft 21 suitably journaled on the frame 12. An upwardly inclined control arm 22, which may have a roll 23 positioned on the end thereof, is also secured to the shaft 21 whereby a rocking movement of the shaft 21 by changing the position of the piston rod 19 in the cylinder 18 will cause the control arm 22 to move through an arc. Hence, the rolls 23, which engage and position the front ends of the bars 15 and 16, will vary the vertical positions of these bars in relation to the upper reach 10 of the conveyor.

Any suitable means can be associated with and connected to the cylinder 18 for controlling the position of the piston rod 19 in relation thereto and thus, if desired, a remote control can be connected to a hydraulic pressure supply line to control the flow of fluid to and from the cylinder 18 to raise or lower the upstream ends of the bars 15 and 16, as these bars are tied together for unitary positioning thereof by suitable means extending therebetween and/or unitary action of the cylinders 18.

The downstream ends of the tracks, or bars 15 and 16 are controlled, as by means of a pair of toggles or lever means 24, one end of each of which engages a support shaft 25 extending transversely of the tracks and operatively engaging means, such as brackets 25a secured to and extending downwardly from the bars 15 and 16. The opposite ends of the toggles 24 are fixedly connected to a shaft 26 that is journaled on the frame 12 and has a control arm 27 fixedly secured thereto and extending therefrom. The control arm 27, in turn, engages with a threaded, vertically extending rod 28, which is positioned

for rotary movement, as by being engaged by a pair of vertically spaced thrust bearings 29 and 30. The rod has a control handle or disc 31 secured thereto whereby the rod 28 can be rotated readily to raise or lower the control arm 27 by accurately controlled increments of movement. Such action moves the arms or links of the toggle 24 with relation to each other to change the vertical position of the downstream ends of the bars 15 and 16 in relation to the end sprockets or positioning drums for the conveyor 3 and the horizontal reach thereof. A cross bar 31 is suitably secured to and extends between the bars 15 and 16 to unify such bars and the positioning thereof.

Any suitable guides (not shown) may extend upwardly from the arms 22 to retain the tracks 15 and 16 in vertical register therewith. Lost-motion slots may be provided in the brackets 25a to permit some upward movement of the tracks 15 and 16 relative to the shaft 25, if desired. Any suitable connection may be provided between the toggle or lever 24, shaft 25, bracket 25a, and track supported thereby to maintain such members in operative association but to permit some limited vertical movement in the tracks 15 and 16 with relation to the shaft 25 and/or lever 24.

The vertical relationships of the bars 15 and 16 and whether they are positioned parallel to or at some slight angle in relation to the normal horizontal upper reach 10 of the conveyor 3 is important in the agitating action to be given to the conveyor, as it moves over the bars 15 and 16. Hence, to provide the desired agitator action on the conveyor 3, a frontrapper bar 32 is secured to and extends along a side of each of the bars 15 and 16, as by a cap screw 33 engaging with a vertically extending frontrapper bar 32. The frontrapper bars are substantially balanced for vertical movement with relation to the bars 15 and 16 at the slotted connections therewith. The frontrapper bar 32 is made of substantially L-shape in vertical section for a short portion of its length by the provision of a foot or bottom flange 35 formed on the rapper bar at the center portion thereof whereby a flat surface 35a is provided extending generally parallel to the lower surface of the bar 15 but normally spaced downwardly therefrom a short distance, as indicated in FIG. 5. Hence, impacts can be provided to these rapper bars 32, as hereinafter described, to aid in shaking dirt through the conveyor 3.

Rear or trailing rapper bars 36 are also pivotally secured, as by pins 37, to the sides of each of the support bars 15 and 16 at the downstream ends thereof. The positioning pins 37 are at the upstream ends of the trailing rapper bars 36 and usually are positioned for only limited arcuate vertical movement immediately below the upper reach 10 of the conveyor 3. Such trailing rapper bars 36 may be of generally T-shape in section for a portion of their length and have a lower portion 36a thereof spaced vertically downwardly a short distance from the lower surfaces of the bars 15 and 16. This leaves the rapper bars 36 free for limited pivotal upward movement for agitating action on the upper reach 10 of the conveyor and any contents thereon.

The actual agitating, vibrating, or impact action to be supplied to the conveyor 3 is provided by a pair of driven shafts 38 and 39 that are suitably journaled on the frame 12 and which carry members such as radially extending arms 40 thereon. The arms 40 position members such as rolls 41 at the radially outer ends thereof. The rolls 41 are so positioned on the frame 12 in relation to the bars 15 and 16, that on rotation of the shafts 38 and 39, the arms 40 will cause the rolls 41 thereof to strike against and elevate the frontrapper bars 32 and the trailing rapper bars 36 twice on each rotation of the shafts 38 and 39.

By the means described hereinbefore, the position of the upstream ends of the bars 15 and 16 will be controlled by the cylinders 18 and the piston rods 19 extending

therefrom and these bars can be lowered far enough that the agitator action will move both the front rapper bars 32 and the upstream ends of the bars 15 and 16 to agitate the entire upstream portion of the conveyor reach 10. The vertical relationship of the downstream ends of the bars and the conveyor 3 will be regulated by the control arm 27 and its engagement with the threaded rod 28 whereby such bars can be substantially parallel to the upper reach of the conveyor, or the support bars can be at a slight angle to this horizontal conveyor reach. The 10 motion of the trailing rapper bars 36 can be limited by a slotted connection to the bars 15 and 16.

By the different positionings of the front rapper bars 32 in relation to that for the trailing rapper bars 36, a generalized impact can be provided for the conveyor 3 at 15 its upstream end, whereas more of a specialized, or localized vibratory, or impact action will be applied to the conveyor 3 in the downstream end thereof as the free downstream ends of the trailing rapper bars 36 are elevated by the rolls 41 on the shaft 39 contacting such trailing rapper bars to knock them rapidly vertically upwardly.

It will be realized that the drive shafts 38 and 39 can be rotated from any conventional power source at any reasonable rate of speed. This continual agitation or vibration of the conveyor 3 and the contents thereon will cause lumps of dirt, for example, on the conveyor, to be shaken or vibrated apart so that the dirt will fall through both the upper reach 10 of the conveyor and the associated lower reach of the conveyor and pass from the 30 vehicle in any manner, usually directly, back to the ground.

Obviously, any conveyor or elevator means 2 may be used to deposit the mixture of materials, such as freshly dug dirt and articles growing in the dirt, onto the conveyor 3 for processing therein. Likewise, any suitable receiving means, or further processing means will be associated with the conveyor 3 at its discharge end for further processing the materials discharged therefrom. The controlled vibratory separating action can be readily varied to suit the conditions required for the dirt and articles being processed. Hence, it is believed that the objects of the invention have been achieved.

While one complete embodiment of the invention has been disclosed herein, it will be appreciated that modification of this particular embodiment of the invention may be resorted to without departing from the scope of the invention as defined in the appended claims.

What I claim is:

1. In an apparatus including a frame, an endless apertured conveyor, and means positioning said conveyor on said frame for movement through a fixed path including an upper horizontal reach, the improvement comprising a pair of first-named bars extending longitudinally of said conveyor immediately below said reach thereof, adjustable support means engaging each end of said bars and securing them to said frame to vary the position of said bars in relation to said conveyor in said reach thereof,
2. In an apparatus including a frame, an endless apertured conveyor, and means positioning said conveyor on said frame for movement through a fixed path including an upper horizontal reach, the improvement comprising a front rapper bar secured to each of said first-named bars by lost-motion means and movable thereabove for the length of said front rapper bar to strike said conveyor,
3. In an apparatus including a frame, an endless apertured conveyor, and means positioning said conveyor on said frame for movement through a fixed path including an upper horizontal reach, the improvement comprising a rear rapper bar pivotally secured to each of said first-named bars and movable thereabove in only the downstream portion of said rear rapper bar to strike said conveyor, and
4. In an apparatus including a frame, an endless apertured conveyor, and means positioning said conveyor on said frame for movement through a fixed path including an upper horizontal reach, the improvement comprising a positioning means extending longitudinally of said conveyor immediately below said reach thereof, adjustable support means engaging said positioning means and securing it to said frame to vary the position thereof in relation to said conveyor in said reach thereof,
5. In an apparatus including a frame, an endless apertured conveyor, and means positioning said conveyor on said frame for movement through a fixed path including an upper horizontal reach, the improvement comprising a front rapper bar operatively carried by said positioning means and movable thereabove to strike said conveyor at an upstream end thereof,
6. In an apparatus including a frame, an endless apertured conveyor, and means positioning said conveyor on said frame for movement through a fixed path including an upper horizontal reach, the improvement comprising a rear rapper bar operatively carried by said positioning means and movable thereabove to strike said conveyor at a downstream end thereof, and
7. In an apparatus including a frame, an endless apertured conveyor, and means positioning said conveyor on said frame for movement through a fixed path including an upper horizontal reach, the improvement comprising a positioning means extending longitudinally of said conveyor immediately below said reach thereof, adjustable support means engaging said positioning means and securing it to said frame to vary the position thereof in relation to said conveyor in said reach thereof,
8. In an apparatus for separating dirt from articles dug from the ground,
9. In an apparatus for separating dirt from articles dug from the ground, an open frame-type endless conveyor, frame means,
10. In an apparatus for separating dirt from articles dug from the ground, a pair of sprocket and shaft means journaled on longitudinally spaced portions of said frame means and engaging said conveyor to position it with an upper horizontally extending reach,
11. In an apparatus for separating dirt from articles dug from the ground, a pair of parallel supports operatively positioned on said frame immediately below said conveyor at said reach thereof to support said conveyor intermediate said sprocket and shaft means,
12. In an apparatus for separating dirt from articles dug from the ground, said conveyor having an article receiving and an article discharge end,
13. In an apparatus for separating dirt from articles dug from the ground, a first-named rapper bar movably secured to each of said supports in controlled relation thereto and movable up into contact with said conveyor adjacent the article receiving end thereof,
14. In an apparatus for separating dirt from articles dug from the ground, a second rapper bar pivotally secured adjacent one end to each of said supports downstream of said first-named rapper bar and movable at its other end up into localized contact with said conveyor,
15. In an apparatus for separating dirt from articles dug from the ground, driven cam means operably engaging said rapper bars to move them up into contact with said conveyor to strike it from below to aid dirt thereon in falling therethrough, and
16. In an apparatus for separating dirt from articles dug from the ground, means carried by said frame means and engaging said supports for adjusting the positions of said supports with relation to said cam means to vary the intensity of contact of said cam means with said rapper bars.
17. In an apparatus for separating dirt from articles dug from the ground,
18. In an apparatus for separating dirt from articles dug from the ground, an open frame-type endless conveyor, frame means,
19. In an apparatus for separating dirt from articles dug from the ground, a pair of sprocket and shaft means journaled on longitudinally spaced portions of said frame means and engaging said conveyor to position it with an upper horizontally extending reach,
20. In an apparatus for separating dirt from articles dug from the ground, a pair of parallel supports operatively positioned on said frame immediately below said conveyor at said reach thereof,
21. In an apparatus for separating dirt from articles dug from the ground, said conveyor having an article receiving and an article discharge end,
22. In an apparatus for separating dirt from articles dug from the ground, a rapper bar movably positioned adjacent and secured to each of said supports in controlled relation thereto and movable into contact with said conveyor,
23. In an apparatus for separating dirt from articles dug from the ground, a driven means operably engaging each of said rapper bars to move them up into contact with said conveyor to strike it from below to aid dirt thereon in falling therethrough, and

2. In an apparatus including a frame, an endless apertured conveyor, and means positioning said conveyor on said frame for movement through a fixed path including an upper horizontal reach, the improvement comprising a positioning means extending longitudinally of said conveyor immediately below said reach thereof, adjustable support means engaging said positioning means and securing it to said frame to vary the position thereof in relation to said conveyor in said reach thereof,
3. In an apparatus for separating dirt from articles dug from the ground,
4. In an apparatus for separating dirt from articles dug from the ground, an open frame-type endless conveyor, frame means,
5. In an apparatus for separating dirt from articles dug from the ground, a pair of sprocket and shaft means journaled on longitudinally spaced portions of said frame means and engaging said conveyor to position it with an upper horizontally extending reach,
6. In an apparatus for separating dirt from articles dug from the ground, a pair of parallel supports operatively positioned on said frame immediately below said conveyor at said reach thereof to support said conveyor intermediate said sprocket and shaft means,
7. In an apparatus for separating dirt from articles dug from the ground, said conveyor having an article receiving and an article discharge end,
8. In an apparatus for separating dirt from articles dug from the ground, a first-named rapper bar movably secured to each of said supports in controlled relation thereto and movable up into contact with said conveyor adjacent the article receiving end thereof,
9. In an apparatus for separating dirt from articles dug from the ground, a second rapper bar pivotally secured adjacent one end to each of said supports downstream of said first-named rapper bar and movable at its other end up into localized contact with said conveyor,
10. In an apparatus for separating dirt from articles dug from the ground, driven cam means operably engaging said rapper bars to move them up into contact with said conveyor to strike it from below to aid dirt thereon in falling therethrough, and
11. In an apparatus for separating dirt from articles dug from the ground, means carried by said frame means and engaging said supports for adjusting the positions of said supports with relation to said cam means to vary the intensity of contact of said cam means with said rapper bars.
12. In an apparatus for separating dirt from articles dug from the ground,
13. In an apparatus for separating dirt from articles dug from the ground, an open frame-type endless conveyor, frame means,
14. In an apparatus for separating dirt from articles dug from the ground, a pair of sprocket and shaft means journaled on longitudinally spaced portions of said frame means and engaging said conveyor to position it with an upper horizontally extending reach,
15. In an apparatus for separating dirt from articles dug from the ground, a pair of parallel supports operatively positioned on said frame immediately below said conveyor at said reach thereof,
16. In an apparatus for separating dirt from articles dug from the ground, said conveyor having an article receiving and an article discharge end,
17. In an apparatus for separating dirt from articles dug from the ground, a rapper bar movably positioned adjacent and secured to each of said supports in controlled relation thereto and movable into contact with said conveyor,
18. In an apparatus for separating dirt from articles dug from the ground, a driven means operably engaging each of said rapper bars to move them up into contact with said conveyor to strike it from below to aid dirt thereon in falling therethrough, and

means adjusting the positions of said supports with relation to said conveyor reach to vary the intensity of contact of said driven means with said rapper bars.

5. In apparatus including a frame, an endless apertured conveyor, means positioning said conveyor on said frame for movement through a fixed path including an upper horizontal reach, the improvement comprising

a pair of first-named bars extending longitudinally of said conveyor immediately below said reach thereof to support said conveyor,

a pair of individually adjustable support means engaging corresponding ends of said bars to vary their positions in relation to said reach of said conveyor, means pivotally connecting the downstream ends of said bars to said frame,

a rapper bar operatively carried by and secured to each of said first-named bars and movable thereabove to strike said conveyor, and

driven cam means positioned to strike said rapper bars and knock them against said conveyor with a variable force dependent upon the positioning of said bars in relation to said cam means whereby dirt in a mixture of dirt and dug articles on said conveyor is shaken and is urged to drop through said conveyor.

6. In apparatus including a frame, an endless apertured conveyor, and means positioning said conveyor on said frame for movement through a fixed path including an upper horizontal reach, the improvement comprising a pair of first-named bars extending longitudinally of and substantially parallel to said conveyor immediately below said reach thereof to aid in supporting said conveyor,

individually adjustable support means engaging an end of said bars and securing them to said frame to vary the angular position of said bars in relation to said conveyor in said reach thereof,

a front rapper bar operatively carried by and secured to each of said first-named bars and movable thereabove to strike said conveyor,

a rear rapper bar pivotally carried by and secured to each of said first-named bars and movable thereabove to strike said conveyor, and

driven means positioned to strike said rapper bars and knock them against said conveyor to elevate it with a force dependent upon the positioning of said bars in relation to said last-named means where more severe impacts can be given to said conveyor in said reach portion thereof at one portion of said reach than at another portion thereof.

7. In an apparatus including a frame, an endless apertured conveyor, and means positioning said conveyor on said frame for movement through a fixed path including an upper horizontal reach, the improvement comprising

a pair of first-named bars extending longitudinally of said conveyor immediately below said reach thereof, adjustable support means engaging each end of said bars and securing them to said frame to vary the position of said bars in relation to said conveyor in said reach thereof,

a front rapper bar,

lost-motion means securing a said front rapper bar to each of said first-named bars and movable thereabove for the length of said front rapper bar to strike said conveyor,

means to limit the upward movement of said rapper bars in relation to said first-named bars carried by said rapper bars, and

driven cam means positioned to strike said rapper bars and knock them against said conveyor to elevate it with a force dependent upon the relative positioning of said bars in relation to said cam means where more severe impacts can be given to said conveyor in said reach portion thereof at one portion of said reach than at another portion thereof.

8. In an apparatus including a frame, an endless apertured conveyor, and means positioning said conveyor on said frame for movement through a fixed path including

25 an upper horizontal reach, the improvement comprising a positioning means extending longitudinally of said conveyor immediately below said reach thereof, adjustable support means engaging said positioning means and securing it to said frame to vary the position thereof in relation to said conveyor in said reach thereof,

30 a front rapper bar operatively secured to said positioning means by lost-motion and movable thereabove to strike said conveyor at an upstream end thereof, a rear rapper bar operatively pivotally secured to said positioning means and movable thereabove to strike said conveyor at a downstream end thereof,

35 all of said rapper bars being associated with the sides of said positioning means and having portions below but aligned with said positioning means to limit upward movement of said rapper bars, and

40 driven means positioned to strike said rapper bars and knock them against said conveyor to elevate it with a force dependent upon the relative positioning of said bars in relation to said driven means where more severe impacts can be given to said conveyor in said reach portion thereof at one portion of said reach than at another portion thereof.
